[57] CLAIM

The ornamental design for a lidded storage bin, as shown and described.

DESCRIPTION

FIG. 1 is a perspective view of a lidded storage bin showing my new design;

FIG. 2 is a right side elevation thereof; the left side elevation being a mirror image of the right side elevation;

FIG. 3 is a top plan view thereof;

FIG. 4 is a front elevation thereof;

FIG. 5 is a rear elevation thereof; and

FIG. 6 is a bottom plan view thereof.

FIG. 1

FIG. 2

FIG. 3

FIG. 4

FIG. 5

FIG. 6
